UNITED STATES PATENT OFFICE.

MILES EDWARD LOEHR, OF WARSAW, INDIANA.

PUMP AND CLEANER FOR ACETYLENE-GAS GENERATORS.

1,193,907.

Specification of Letters Patent.

Patented Aug. 8, 1916.

Application filed October 3, 1914. Serial No. 864,926.

To all whom it may concern:

Be it known that I, MILES E. LOEHR, a citizen of the United States, residing at Warsaw, in the county of Kosciusko and State of Indiana, have invented certain new and useful Improvements in Pumps and Cleaners for Acetylene-Gas Generators; and I do hereby declare the following to be a full, clear, and exact description of the invention, such as will enable others skilled in the art to which it appertains to make and use the same.

This invention comprehends certain new and useful improvements in pumps and cleaners for acetylene gas generators and has for its primary object to provide a device of this character which may be readily incorporated in acetylene gas generators of the form now in use to remove the residue from a generator casing with one operation.

The invention has for another object to provide a pump and cleaner of this character including a telescoping discharge pipe positioned between the generator and the generator casing so that the pump or discharge pipe may be moved out of position between the generator and casing when not in use.

The invention has for another object to provide a pump and cleaner for acetylene gas generators which will be of such form that the operative parts of the cleaner may be positioned beneath the bottom of the generator with the latter supporting upon the arms employed for spacing the cleaner from the inner wall of the generator casing.

The invention has for a further object to provide a pump and cleaner for acetylene gas generators which will be of such construction and operation that the pump and cleaner may both be operated with one hand to gather the residue from the bottom of the casing of the generator and convey the same to the discharge pipe to be sucked up through the same by the piston of the pump.

The invention has for a still further object to generally improve and simplify the construction and operation of a device of this character and increase the efficiency thereof without materially increasing the cost of the same.

With the above and other objects in view as will become more apparent as the description proceeds, the invention consists in certain novel features of construction, combination and arrangement of parts as will

be hereinafter more fully described and claimed.

For a complete understanding of my invention, reference is to be had to the following description and accompanying drawings, in which—

Figure 1 is a vertical section through a generator and casing with my pump and cleaner positioned therein, portions of my invention being shown in section, Fig. 2 is an enlarged elevation, partly in section of the cleaner, and lower portions of the generator casing, Fig. 3 is a detail perspective view of the revolving cleaning spout removed, and Fig. 4 is a detail view of the reciprocating pump and cleaner rod with the parts carried thereby removed and the pump handle turned to swing the reciprocating pump rod and plunger to one side.

Referring more particularly to the drawings, in which similar reference characters designate corresponding parts throughout the several views, 1 designates the casing within which the tank 2 of an acetylene gas generator is positioned. The bottom 3 of the tank 2 rests upon the outwardly directed horizontal ends 4 of the inclined spacing arm 5 extending from the flange 6 formed on the lower downwardly turned end 7 of the discharge pipe 8 of the pump, it being understood that the ends 4 of the arm 5 have their free extremities 9 directed downwardly and engaged against the inner face of the casing 1 and are preferably secured to the same in some well known or preferred manner. The flange 6 is positioned in the longitudinal center of the casing 1 a spaced distance above the bottom thereof, while the main portion of the discharge pipe 8 extends vertically between the tank 2 and casing 1. The lower portion of said pipe 8 is directed inwardly in a horizontal plane as shown at 10 before being bent or curved downwardly. An upper discharge pipe section 11 is telescopically mounted upon the discharge pipe 8 and has an enlarged or flared upper end 12 with a spout 13 projecting from the side thereof, the upper end of the discharge pipe section 11 being preferably closed, as shown at 14. The upper discharge pipe section 11 also has a downwardly directed hook 15 formed on its outer face for engagement over the upper edge of the casing 1 to support said pipe section 11 in extended position with the discharge spout 13 directed outwardly from said casing 1.

100
105
110

Reciprocally mounted through the end 14 of the extension pump discharge pipe 11 is the reciprocating pump rod 16 which has a valved piston 17 mounted on its lower end 5 within the discharge pipe 8 above the normally closed flap valve 18 in said discharge pipe 8, whereby upon reciprocation of the rod 16 by means of the handle 19 secured to the upper end thereof, the piston 17 will be 10 moved longitudinally in said discharge pipe 8 to draw the residue gathered from the bottom of the casing 1 outwardly through said pipe 8 and extension pipe 11 and out of the discharge spout 13.

15 The handle 19 is in the form of a transverse strip and has depending from its outer ends the reciprocating rod 20 which has the downwardly inclined link 21 extended therefrom with the longitudinal slot 22 formed therein, within which engages a pin 23 mounted upon the upper end of the rock arm 24 to rock the same upon a central pivot pin 25. The pivot pin 25 is extended to a suitable support, (not shown) 25 extending inwardly from the sides of the casing 1 a spaced distance from the bottom thereof. As the handle 19 is moved upwardly and downwardly to reciprocate the pump piston rod 16, the rod 20 will also be reciprocated, thereby moving upwardly and downwardly. The inclined link 21 which is rigid with the rod 20, allows the pin 23 to travel from one end to the other of the slot 22 and thereby rocks the rock arm 24 30 upon its pivot 25 to swing horizontally a pawl operating rod 26 which has its outer end pivoted in the bifurcated lower end of the rock arm 24 while the inner end of the rod 26 is pivoted in the spaced arms of the stationary bracket 27 secured upon flange 35 40 of the downwardly directed end 7 of the discharge pipe 8, thereby moving the pawl 28 into engagement with the ratchet wheel 29 secured around the upper end of the rotating sleeve 30 to rotate said sleeve 30 45 upon the lower extremity of the discharge pipe 8. The rotary sleeve 30 has its lower end closed while its upper end is open and a pivot strap 31 depends from the bottom 50 of said sleeve 30 and is engaged in a suitable bearing slot 32 mounted on the bottom of the casing 1.

A residue revolving gathering finger 33 which is of substantially triangular form 55 in plan has its inner end connected with the outer face of the rotary sleeve 30 while one side of the gathering finger, preferably the forward side is open and the bottom of said finger has its central portion cut away, as 60 shown at 34, whereby the residue in the bottom of the casing 1 may be readily gathered as the sleeve 30 and finger 33 are rotated upon upward and downward movement of the handle 19 and the rods 16 and 65 20 so that the residue may be forced into

the center of the finger 33 to enter the outer end of the projecting pipe 35 and be conveyed by the same to the interior of the sleeve 30, at which place it is drawn upwardly upon operation of the handle 19, as 70 stated. The conducting pipe 35 is within the finger 33 and extends from the center thereof to the inner end and has communication with the interior of the sleeve 30. The outer curved end 36 of the finger 33 is 75 positioned adjacent the side or vertical wall of the casing 1, thereby causing the finger 33 to gather all of the residue between the rotating sleeve 30 and the side walls of the casing 1 as the sleeve 30 and finger 33 80 are rotated, the bottom of the sleeve 30 resting upon the bottom of the casing 1.

From the foregoing it will be readily seen that the residue may be gathered from the bottom of the casing 1 and drawn upwardly 85 through the discharge pipes 8 and 11 and forced out of the discharge spout 13 with one operation which may be accomplished with one hand of the operator. It will also be seen that the construction and operation 90 of the parts of this device are extremely simple and the apparatus may be readily incorporated in generators of the type now in general use without altering the construction thereof, it simply being necessary to 95 provide a casing of greater depth and larger than the tank of the generator.

While the preferred embodiment of the invention has been shown and illustrated, 100 it will be understood that minor changes in the details of construction and arrangement of parts may be made within the scope of the appended claims without departing from the spirit of the invention or sacrificing any of the advantages thereof.

What is claimed is:—

1. A device of the class described including the combination with a gas generator casing, brackets secured in said casing adjacent the bottom thereof, and a tank seated in said gas generator casing upon the upper portions of the brackets, of a discharge pipe positioned vertically between the casing and tank, the upper end of said pipe extending outwardly beyond the upper edges of the 110 casing, the lower end of said pipe directed inwardly and downwardly and positioned directly under the bottom of the tank, a rotary sleeve carried on the lower end of said pipe, a residue gathering member carried by said rotary sleeve, a ratchet wheel positioned on the upper end of said rotary sleeve, an arm connected to said sleeve and provided with a pawl to engage said ratchet wheel for rotating the same, a piston rod 115 slidably mounted in said pipe, a cross arm connected to the upper end of the piston rod, an operating rod connected at one end of the free end of the cross arm and extending 120 downwardly from along the outside of 125 130

said pipe, the free end connected to the first mentioned arm for rotating said rotary sleeve and turning the residue gathering members for sucking the residue up into the 5 pipe and out of the same.

2. The combination of an acetylene gas generator casing and tank, said tank positioned in said casing and held spaced from the walls thereof and elevated above the 10 bottom, of a discharge pipe positioned between the casing and the walls of the tank, the upper end of said pipe projecting beyond the upper edges of said casing, and means for holding the same positioned therein, the 15 lower end of said pipe directed horizontally in toward the center thereof and directed downwardly, the downwardly projecting portion positioned directly under the bottom of the tank, a rotary sleeve carried on the 20 lower end of said pipe, a gathering member carried by said rotary sleeve, a ratchet wheel positioned on the upper end of said rotary sleeve, an arm connected to said sleeve and provided with a pawl to engage said ratchet 25 wheel for rotating the same, a piston slidably mounted in the pipe, a cross arm connected to the upper end of the piston rod, an operating rod connected at one end to the free end of the cross arm and extending 30 downwardly along the outside of said pipe, the free end connected to the first mentioned arm, whereby upon movement of said arm the first named arm will be rotated and in turn rotate said sleeve moving the gathering 35 member around the bottom of the tank gathering the residue up through the same and out through the pipe.

3. A device of the class described comprising the combination with the casing and tank of a generator; of a discharge pipe projecting upwardly between said tank and casing, a discharge spout for said discharge pipe, the lower end of the discharge pipe being directed inwardly and curved downwardly, a flange formed on the lower end 40 of said discharge pipe, supporting means for the tank projecting upwardly and outwardly from said flange, a sleeve rotatably mounted upon the lower end of said discharge pipe, a ratchet wheel mounted on 45 said sleeve, a gathering finger projecting from one side of the sleeve for gathering the residue from the bottom of the casing, a conducting pipe leading from the center of the gathering finger to the interior of the sleeve 50 to conduct the residue to the same, means within the discharge pipe for drawing the material upwardly through the same and forcing the residue outwardly through the discharge pipe, means for returning the discharge pipe in position, a pawl engaged 55 with the ratchet wheel, means for operating the pawl to rotate the sleeve and gathering finger, and connections between the last mentioned means and the means within the discharge pipe, whereby the sleeve and gathering finger may be operated upon operation 60 of the means within the discharge pipe.

In testimony whereof I affix my signature in presence of two witnesses.

MILES EDWARD LOEHR.
